CORE TAKING APPARATUS

George G. Harrington, Houston, Tex., assignor to
Reed Roller Bit Company, Houston, Tex., a cor-
poration of Texas

Application August 27, 1937, Serial No. 161,184

15 Claims. (Cl. 255—72)

This invention relates in general to sample taking devices, and more particularly to a device for taking cores from the formation at the bottom of a well being drilled. The invention relates especially to an arrangement whereby the space adapted to receive the core as it is cut may be kept free from cutting sand and other debris during the time it is being lowered into the well.

In the past, various arrangements have been devised for receiving cores cut from the formation at the bottom of a well being drilled, and for removing such cores to the surface of the ground so that information regarding the nature of the formation may be obtained. Such devices have for the most part, however, been open at both ends during the time that they were being lowered into the well, so that mud or other liquid in the well could pass into and up through the core barrel as it was being lowered. This naturally caused a considerable accumulation within the core barrel of cuttings or other debris which might be suspended by the liquid in the well.

It is, therefore, an object of this invention to provide a sample taking device including a core barrel which may be lowered into a well without the passage therethrough of the liquid contained in the well, and consequently without the accumulation therein of cuttings and other debris which might be suspended in such liquid.

It is a further object to provide a device of the character set forth in which the core barrel may be lowered to core taking position without taking in matter which might contaminate or affect the value of the core to be taken. It is a further object to provide a means for retaining a core within a core barrel, and provide an arrangement whereby such means will be held in inactive position until the core is moved upwardly in the core barrel.

It is a further object to provide a device of the character set forth in which the upper end of the core barrel will be normally closed during the time it is being lowered into a well, but which may be then opened to permit upward flow through the core barrel during the taking of a core.

With the foregoing and other objects in view, this invention contemplates the various parts and combinations set forth in the accompanying drawing, and in the following description, it being understood, however, that said drawing and description are by way of illustration and example only, and are not to be taken as in any

way a limitation upon the scope of this invention.

Referring now to the drawing in which like numerals indicate corresponding parts throughout:

Fig. 1 is a view partly in vertical cross section illustrating the valve structure at the upper end of a core barrel constructed in accordance with this invention.

Fig. 2 is a view in vertical cross section illustrating a continuation of the lower portion of the structure shown in Fig. 1.

Fig. 3 is a horizontal cross section taken along the line 3—3 of Fig. 2.

In connection with this invention there is employed a core bit having a head 1 and outer and inner roller cutters 2 and 3 which cut an annular opening and form the core 4. The head 1 is provided with passageways 5 and 6 located in its walls for the purpose of conveying washing fluid to the cutters 2 and 3 just referred to. The bit is internally threaded at its upper end to receive the fitting 7, this fitting being likewise internally threaded at its upper end to receive the drill collar 8. The joint between the member 7 and the drill collar 8 is preferably welded so as to in effect combine these members into one integral structure.

Within the drill collar 8 is located the core barrel 9 upon the lower end of which is mounted a fitting 10 having a slightly reduced internal diameter. A sleeve 11 having an internally tapered seat 12 at its lower end is threaded securely upon the lower end of the fitting 10, the seat 12 being adapted to receive the lower portions of the core catcher elements 13. These core catcher elements 13 are in the form of slips so designed that when they are moved downwardly against the seat 12 they are caused to at the same time move inwardly in a radial direction and thus grip the core or whatever may be located within the core barrel.

In addition to the catcher elements 13 there are also provided a different form of catcher elements 14, these being in the form of sharpened fingers or knives pivoted at their lower ends 15 to the vertically slideable ring 16. The catcher elements 13 are likewise mounted on this ring by means of springs 17 which are secured to the elements 13 and to the ring 16. It will be noted that the ring 16 is provided with openings and recesses for receiving the various core catcher elements to permit a full hole opening during upward motion of a core into the barrel. The teeth 18 on the elements 13 are inclined in an

upward direction so as to permit free upward movement of a core and to catch and restrain any downward movement thereof.

In accordance with this invention, the core catcher elements just referred to are held in their retracted or inoperative position during the lowering of the core barrel into a well by means of a sleeve 19 which is slidably positioned within the lower end of the fitting 10 and extends 10 between the core catcher elements. This sleeve 19 may be in the form illustrated in Fig. 2. For the purpose of preventing any downward motion of the sleeve 19, beyond the position in which it is illustrated in Fig. 2, this sleeve is provided on its outer surface with a short section of leaf spring 22 which may be engaged with one of the teeth on the core retaining member 13. It will be seen that by the structure just outlined, the core catcher elements will be effectively retained and protected from the fluid in the well until the core actually rises into the core barrel.

At its upper end the sleeve 19 is provided with a head 20 secured therein by suitable means 25 such as by welding and serving to close the passage therethrough. Sealing rings 21 are also provided on the sleeve 19 to form a fluid tight contact with the interior of the fitting 10. The sleeve 19 and its cooperating parts thus form a 30 fluid tight plug for the lower end of the core barrel when in the position shown in Fig. 2.

At its upper end, the core barrel 9 is provided with a valve fitting 23 having an opening therethrough. Intermediate its ends, this opening is 35 interrupted by a partition 24 having smaller openings 25 therethrough. At its lower end, a seat 26 is provided for a ball valve 27, this seat being held in position within the fitting 23 by means of a nut 28 or the like. Similarly, at 40 its upper end, the fitting 23 is provided with a seat member 29 for a ball valve 30, this seat member being held in position by a nut 31. The nut 31 adjacent its lower end is provided with lateral openings 32 which are adapted to 45 substantially register with the lateral openings 33 through the wall of the valve fitting.

The nut 28 is hollow so that liquid may pass freely therethrough. The nut 31, however, has an opening through its upper end of only sufficient size to receive the plunger 34, which has a nut 35 on its upper end. This plunger 34 is adapted to receive a weight to be dropped in through the drill stem in the manner hereinafter described, and under the influence of such weight 50 to move downwardly and unseat the ball valve 30 against the tension of the spring 36 so that liquid may flow upwardly through the nut 28, past the valve 27, through the openings 25 and out through the openings 32 and 33.

60 The core barrel is supported within the drill collar upon the sleeve 11, which in turn rests at its lower end upon a shoulder 37 within the bit head 1. The core barrel is held against upward movement by laterally extending lugs 38 65 in engagement with the lower end of the member 7. It is held in alignment at its upper end by means of the laterally extending guide lugs 39.

At its upper end the drill collar 8 is externally 70 threaded to receive the lower end of a collar 40, this joint preferably being welded so as to integrally join these parts. The section 41 of the drill stem is threadedly engaged within the upper end of the collar 40.

75 In the operation of the device the sleeve 19

is positioned within the lower end of the core barrel as shown and the core barrel may be filled with water or some other suitable liquid, preferably, however, with a fluid which will resist corrosion of the core barrel. The barrel is then closed at its lower end by the sleeve 19 and its head 20 and at its upper end by the valves 27 and 30, and is full of a clear fluid. No mud or debris can enter the bottom because of the sleeve 19 and head 20 and this sleeve cannot be moved upwardly into the core barrel because the barrel is full of fluid which is prevented from escaping therefrom by the valve 30. No mud can enter the top because of the valve 27. Consequently, the core barrel may be lowered 10 into the well without contamination.

When the bottom of the well has been reached, a weight is then dropped in through the drill stem to cause the plunger 34 to move downwardly and unseat the valve 30 after which fluid may 20 pass upwardly from the core barrel through the valves 27 and 30. The coring is then started and as the core moves upwardly into the core barrel it pushes the sleeve member 19 upwardly until the top of the core barrel is reached. This, of course, releases the core catchers and retainers for operation, and when the core has been cut it can be removed from the well in the customary manner. It will be noted that after a short initial movement, the sealing means 21 will clear 25 the fitting 10 of reduced diameter, and the sleeve 19 can freely travel up in the core barrel.

It will be further appreciated that various changes and modifications may be made in the parts illustrated and described without departing 30 from the spirit and scope of this invention as defined in the following claims.

From the foregoing it will be appreciated that there has been set forth an apparatus capable of carrying out all the objects and advantages 40 sought by this invention as hereinbefore set forth.

Having described my invention, I claim:

1. In a sample taking device, a core barrel having an opening adjacent its upper end, valve 45 means for preventing outward flow through said opening, and means for sealing the lower end of said core barrel, said means being movable freely upwardly during the taking of the core.

2. In a sample taking device, a core barrel having an opening adjacent its upper end, and valve 50 means for preventing outward flow through said opening, and a freely movable sealing plug slidably mounted in said core barrel adjacent the lower end thereof.

3. In a sample taking device, a core barrel having an opening adjacent its upper end, and an opening at its lower end, means for sealing both of said openings during the lowering of the core barrel into the well, and means for releasing at 60 the sealing means for the opening at the upper end of the barrel.

4. In a sample taking device, a core barrel having an opening adjacent its upper end and an opening at its lower end, means for closing both 65 of said openings against outflow from said core barrel, and means operable at will for rendering the means for closing the upper opening ineffective.

5. In a sample taking device, a core barrel having an opening adjacent its upper end and an opening at its lower end, means for closing said upper opening, against outflow from said core barrel, means operable at will for rendering said last mentioned means ineffective, and means slid- 70 75

- ably mounted in said core barrel for closing said lower opening against outflow.
6. In a sample taking device, a core barrel having an opening adjacent its upper end and an opening at its lower end, means for closing said upper opening against outflow from said core barrel, means for rendering said last mentioned means ineffective when desired, means slidably mounted in said core barrel for closing said lower opening against outflow, and a filling fluid within said core barrel for preventing upward movement of said last mentioned means prior to the time that the means for closing said upper opening is rendered ineffective.
- 15 7. In a sample taking device, a core barrel having an opening adjacent its upper end and an opening at its lower end, means for closing said upper opening against outflow from said core barrel, means for rendering said last mentioned means ineffective when desired, means slidably mounted in said core barrel for closing said lower opening against outflow, and an anti-corrosive filling fluid within said core barrel for preventing upward movement of said last mentioned means prior to the time that the means for closing said upper opening is rendered ineffective.
8. In a device for closing the lower end of a core barrel, a sleeve, packing means about the sleeve adapted to form a fluid-tight, sliding seal 30 with the walls of the core barrel at the lower end thereof, and a head closing the upper end of said sleeve.
9. In a sample taking device, a core barrel having a lower end zone of slightly reduced internal 35 diameter, and a closure member having a slideable sealing engagement with the walls of said lower end zone of reduced diameter, but no sealing engagement with the barrel above said zone.
10. In a sample taking device, a core barrel 40 having a lower end zone of slightly reduced internal diameter, a closure member having a slideable sealing engagement with the walls of said lower end zone of reduced diameter, but no sealing engagement with the barrel above said zone and means for limiting downward sliding movement of said closure member in the core barrel to prevent said closure member from falling out of the core barrel.
11. In a sample taking device, a core barrel 45 having a lower end zone of slightly reduced internal diameter, core catcher elements disposed about said core barrel below the upper end of
- said end zone, a closure member having a slideable sealing engagement with the walls of said lower end zone, and means on said closure member for engaging said core catcher element to limit downward movement of said closure member. 5
12. In a sample taking device, a core barrel having a lower end zone of an internal diameter slightly smaller than the remainder of said barrel, core catcher elements disposed about said core barrel below the upper end of said end zone, and a 10 closure member having slideable sealing engagement with the walls of said lower end zone, and having a part normally overlying said core catcher elements to protect the same from becoming clogged with drilling fluid and debris during the 15 lowering of the core barrel into a well.
13. In a sample taking device, a core barrel having a lower end zone of an internal diameter slightly less than the remainder of said barrel, core catcher elements disposed about said core 20 barrel below the upper end of said end zone, and a closure member having a slideable sealing engagement with the walls of said lower end zone, said closure member comprising a sleeve having a part overlying said core catcher elements to 25 protect them from becoming clogged with drilling fluid and debris as the core barrel is lowered into a well, a head for closing the passage through said sleeve, and sealing means upon said sleeve forming a sealing engagement with the walls of 30 said lower end zone.
14. In a method of lowering a core barrel into a well, the steps of filling said core barrel with liquid, positively sealing the upper and lower ends of said core barrel against outflow therefrom, 35 lowering said core barrel into the well, opening the upper end of said core barrel to permit outflow therefrom so that said liquid may be exhausted from the core barrel during the taking of the core, and taking a substantially solid core. 40
15. In a method of lowering a core barrel into a well, the steps of filling said core barrel with an anti-corrosive, substantially incompressible fluid, positively sealing the upper and lower ends of said core barrel against outflow therefrom, lowering 45 said core barrel into the well and subsequently rendering ineffective the means for sealing the upper end of said core barrel so as to permit said fluid to be exhausted from said core barrel during the taking of the core. 50

GEORGE G. HARRINGTON.
